(57) **CLAIM**

The ornamental seam design for garment, as shown and
described.

DESCRIPTION

FIG. 1 is a front perspective view of a garment.

FIG. 2 is a rear perspective view of the garment;

FIG. 3 is a front view of the garment;

FIG. 4 is a rear view of the garment;

FIG. 5 is a right side view of the garment;

FIG. 6 is a left side view pair of the garment; and,

FIG. 7 is an underside view of the garment in an alternate
position of use.

The solid line seams comprise the entirety of the claimed
design. The larger broken lines form no part of the claimed
design and the smaller broken lines, which represent stitching
on the seam, form no part of the claimed design.
